UNITED STATES PATENT OFFICE.

WALLACE L. STIMPSON, OF HOPEDALE, MASSACHUSETTS, ASSIGNEE TO DRAPER CORPORATION, OF HOPEDALE, MASSACHUSETTS, A CORPORATION OF MAINE.

BOBBIN-CLEANER ATTACHMENT FOR REPLENISHING LOOMS.
BOBBIN-CLEANER ATTACHMENT FOR REPLENISHING LOOMS.Application filed April 22, 1927. Serial No. 185,723.
Application filed April 22, 1927. Serial No. 185,724.

This invention relates to filling replenishing looms and more particularly to an attachment for such looms to clean the ejected filling carriers as they are discharged from the shuttle during replenishment.

In replenishing looms wherein the filling carrier or bobbins is changed in the shuttle during replenishment, the discharged filling carriers or bobbins contain waste yarn which must be removed therefrom before a fresh supply of filling can be wound upon the bobbins. To insure that all of the filling carriers discharged from the shuttle shall be successively cleaned of waste filling during the loom operation, the present invention provides a bobbin cleaner of the rotary type which in connection with a bobbin support acts to position the bobbin to be cleaned for the cleaning operation, and to insure that incoming filling carriers shall not pass through the cleaning attachment without being cleaned, the present invention provides that the bobbin cleaner shall be moved from bobbin cleaning position to permit the discharge of a cleaned filling carrier or bobbin, and that as it is so moved a bobbin arrester shall act to intercept and arrest the incoming bobbin to be cleaned until the bobbin cleaner has been moved sufficiently towards its bobbin cleaning position to prevent discharge of the incoming bobbin without being cleaned.

In accordance with the present invention, the bobbin cleaner and bobbin arrester are so related that when the bobbin cleaner is moved from bobbin cleaning position, the bobbin arrester will also be moved into its bobbin arresting position, and, as the bobbin cleaner is moved to its bobbin cleaning position, that the arrester will permit the bobbin to be cleaned to move to bobbin cleaning position.

An important feature of the present invention therefore consists of a bobbin cleaner which is actuated on replenishment of filling to move it away from bobbin cleaning position for the discharge of the cleaned bobbin and to cause the bobbin arrester to arrest the incoming bobbin.

The invention, new combination of parts and novel features thereof, will best be made clear from the following description and the

accompanying drawings of one good form thereof.

In the drawings:

Fig. 1 is a perspective view of portions of a replenishing loom provided with the present invention;

Fig. 2 is a section through the bobbin cleaning attachment, showing the position of parts during the bobbin cleaning operation; and

Fig. 3 is a similar section showing the relation of parts on replenishment of filling with the bobbin cleaner raised from its bobbin cleaning position and the bobbin arrester raised to intercept the incoming filling carrier or bobbin.

The loom frame 1 may be of usual construction and mounted on the breast beam 2 thereof is the hopper stand 3 on which is mounted the rotary hopper containing a series of filling carriers or bobbins 4 which are successively moved to replenishing position. Extending from the hopper stand 3 is the stud or dead shaft 5 on which is mounted the transerrer 6 having the downwardly extending arm 7 connected with a dog 8 which, on call for replenishment of filling, is positioned to be struck by a bunter 80 on the lay to operate the replenishing mechanism, and as such replenishing mechanism is of usual type, now well understood in the art, further description thereof appears unnecessary.

The loom frame 1 has secured thereto a bracket 9 having a rim portion 10 on which the bobbin receiver 11 is mounted in fixed position. The bobbin receiver 11 has an open bottom 12 below which is the bobbin can 13 into which the cleaned bobbins are discharged on each replenishment of filling. Extending transversely of the bobbin receiver 11 is the bobbin cleaner 14 which may be supplied with a frictional surface 95 to engage and unwind the filling or waste yarn from the bobbin being cleaned. The side portion 15 of the bobbin receiver is provided with the elongated slot 16, shown as vertically disposed in the present instance, and through such elongated slot 16 the bobbin cleaner 14 extends. The bobbin cleaner 14 is mounted on a shaft 17 supported in a bearing 18 for rotative move-

ment and connected to the outer end of the shaft 17 is a belt pulley 19 which is driven by a belt 20 running over a belt pulley 21 which may be driven from any going part 5 of the loom. The pulley 21 is mounted on a stud or dead shaft 22 supported by a bearing 23 carried by the loom frame, and the pulley 21 is rotated by means of a belt 24 driven from the under or cam shaft 25 by 10 means of a belt pulley 26 rotating therewith.

The bearing 18 for the bobbin cleaner 14 is carried by an arm 27, the rear end portion of which is concentrically mounted with the shaft 22, as indicated in Fig. 1. In the 15 present instance of the invention, the shaft 21 has mounted thereon a sleeve 28 to which the arm 27 is rigidly connected, and means are provided for moving the arm 27 and the bobbin cleaner carried thereby, on replenishment of filling. 20

Mounted on the loom frame is the usual transverse or change shaft 29 to which is connected an arm 30 having adjustably secured thereto an extension 31 by means of 25 a bolt 32 and slot 33, whereby the length of the actuator which is constituted by the arms 30 and 31 may be lengthened or shortened to impart to the bobbin cleaner the desired movement to and from bobbin cleaning 30 position, to permit discharge of a cleaned bobbin.

Pivottally connected to the arm 31 at 34 is the link 35 which is pivoted at 36 to one arm 37 of a bell crank lever, the pivotal point of 35 which may be conveniently carried by a bracket 38 secured to the loom frame. The other arm 39 of the bell crank lever has a pin and slot connection with the bobbin cleaner supporting arm 27, and, as indicated in Fig. 1, this is accomplished by 40 means of a pin 40 extending from the supporting arm 27 and through the slot 41 of the arm 39, the construction being such that upon rocking movement of the transverse or 45 change shaft 29 in one direction on call for replenishment of filling, the bobbin cleaner 14 will be raised from its bobbin cleaning position to permit the discharge of a cleaned bobbin.

50 As indicated in Fig. 1, a stop is provided for maintaining the bobbin cleaner 14 in its bobbin cleaning position, and such stop may be conveniently formed by a horizontal arm 42 of the bracket 38 on which the arm 27 55 may rest when in its lowered position.

Pivottally mounted at 43 in the bobbin receiver 11 is the incoming bobbin catcher 44, the lower end portion 45 of which is adjacent to and above the bobbin cleaner 14, the 60 construction being such that upon lifting movement of the bobbin cleaner away from bobbin cleaning position, as indicated in Fig. 3, the bobbin arrester 44 will be raised by the bobbin cleaner to catch and arrest the incoming bobbin to be cleaned. If desired, 65

a light spring 46, as indicated in Fig. 1, may 70 yieldingly act upon the bobbin catcher 44 to insure its downward movement with the bobbin cleaner to permit a bobbin on the bobbin catcher to move to bobbin cleaning 75 position. It is preferable in most instances to provide a stop 47 for limiting the downward movement of the bobbin catcher and maintain it in position with the lower end adjacent to and above the bobbin cleaner. 75

Cooperating with the bobbin cleaner 14 to hold the bobbin in cleaning position is a bobbin support 48, the downwardly extending portion of which projects below the bobbin cleaner, with the result that when a 80 bobbin to be cleaned is discharged from the bobbin catcher it may move onto the bobbin support with the yarn on the bobbin in engagement with the bobbin cleaner, as indicated in Fig. 2. 85

Extending from a wall of the bobbin receiver is a stop or plate 49 which may be conveniently supported on a shaft 50, and be provided with an arm 51 for normally holding the stop 49 in its initial position. 90 The lower end portion 52 of the stop cooperates with the lower portion 45 of the bobbin arrester when the latter is in its raised position, as indicated in Fig. 3, to close the passageway leading to the bobbin cleaning position and support the incoming bobbin to be cleaned for movement to cleaning position when the bobbin cleaner is moved to its initial or bobbin cleaning position, the result being that when the bobbin cleaner is moved away from the bobbin support 48 into its upper position to permit the discharge of a cleaned bobbin, and the bobbin arrester is raised into closed position with relation 95 to the stop 49, the incoming bobbin to be cleaned will be held from movement to its cleaning position until after the bobbin cleaner has been moved downwardly a sufficient amount to close the passageway between the bobbin cleaner and the bobbin support 48, so that the incoming filling carrier cannot be discharged without being cleaned. 100 105 110

Since the bobbin cleaner 14 moves on the arc of a circle to and from its bobbin cleaning position, the slot 16 is made sufficiently 115 wide to accommodate for such movement, as indicated in Figs. 2 and 3.

In Fig. 2 a bobbin *a* is indicated as held in bobbin cleaning position relative to the bobbin cleaner 14 by the bobbin support 48, while in Fig. 3 the bobbin cleaner 14 is shown as being moved upwardly from its bobbin cleaning position to permit the discharge of the cleaned bobbin *a* and arrest the movement of the incoming bobbin *b* 120 which was discharged into the bobbin receiver on replenishment of filling. 125

What is claimed is:

1. In a filling replenishing loom, the combination of replenishing mechanism, a bob- 130

bin receiver having a bobbin cleaner, a support for holding a bobbin to be cleaned, and means operated on replenishment of filling for moving the bobbin cleaner away from its cleaning position and the bobbin support to open a discharge passage that a cleaned bobbin may be discharged from the bobbin cleaning position.

2. In a filling replenishing loom, the combination of replenishing mechanism, a bobbin receiver having a bobbin cleaner, a support for holding a bobbin to be cleaned in cleaning relation to the bobbin cleaner, a hinged flap in the bobbin receiver having its free end normally adjacent to the bobbin cleaner, and means actuated on replenishment of filling for moving the bobbin cleaner and hinged flap away from the bobbin support that a cleaned bobbin may be discharged and an incoming bobbin to be cleaned may be arrested by the hinged flap for subsequent movement to cleaning position.

3. In a filling replenishing loom, the combination of replenishing mechanism, a bobbin receiver having a bobbin cleaner, a support for holding a bobbin to be cleaned in cleaning relation to the bobbin cleaner, a hinged flap in the bobbin receiver having its free end normally adjacent to the bobbin cleaner, and means actuated on replenishment of filling for lifting the bobbin cleaner and the free end of the hinged flap away from the bobbin support to discharge a cleaned bobbin and arrest an incoming bobbin to be cleaned for subsequent movement to bobbin cleaning position.

4. In a filling replenishing loom, the combination of a bobbin receiver having a bobbin cleaner, a bobbin support for holding a bobbin in cleaning position, an arm connected to the bobbin cleaner, and means actuated on replenishment of filling for operating said arm to move the bobbin cleaner away from the bobbin support to discharge a cleaned bobbin.

5. In a filling replenishing loom, the combination of a bobbin receiver having a bobbin cleaner, a bobbin support cooperating with the bobbin cleaner to hold a bobbin in cleaning position, means for supporting the bobbin cleaner for movement to and from its normal cleaning position on replenishment of filling to discharge a cleaned bobbin, and an incoming bobbin arrester which

is moved into arresting position as the bobbin cleaner is moved to discharge a cleaned bobbin to insure that the incoming bobbin to be cleaned shall be delayed in its movement to cleaning position.

6. In a filling replenishing loom, the combination of a bobbin receiver having slotted side walls, a bobbin cleaner extending transversely of the bobbin receiver, an arm connected to the bobbin cleaner for moving it in the slotted walls of the bobbin receiver, and means actuated on replenishment of filling for moving the bobbin cleaner relative to the slotted walls of the receiver away from bobbin cleaning position to permit the discharge of a cleaned bobbin and then back to cleaning position.

7. In a filling replenishing loom, the combination of a bobbin receiver, a bobbin cleaner, means for rotating the bobbin cleaner during the loom operation, an arm connected to the bobbin cleaner, and means operating through said arm on replenishment of filling for moving the rotating bobbin cleaner from and to bobbin cleaning position.

8. In a filling replenishing loom, the combination of a bobbin receiver, a bobbin cleaner, a pulley operated by a going part of the loom, a belt and pulley connection therewith to the bobbin cleaner, an arm concentrically pivoted with relation to the first named pulley and supporting the bobbin cleaner, and means actuated on replenishment of filling for swinging said arm to move the bobbin cleaner from and to bobbin cleaning position to effect discharge of a cleaned bobbin.

9. In a filling replenishing loom, the combination of a bobbin receiver and a rotary bobbin cleaner, a bobbin arrester pivotally mounted in the bobbin receiver with its free end overlying the bobbin cleaner, a bobbin support cooperating with the bobbin cleaner to position the bobbin to be cleaned, and means actuated on replenishment of filling for moving the bobbin cleaner away from the bobbin support to discharge a cleaned bobbin and causing it to move the bobbin arrester to bobbin arresting position and then returning the bobbin cleaner and with it the bobbin arrester to initial positions.

In testimony whereof, I have signed my name to this specification.

WALLACE I. STIMPSON.
